COMBINED MOUNTING AND PROTECTIVE HOUSING FOR LOUD-SPEAKERS

Eberley R. Ethington, Santa Monica, Calif.

Application December 9, 1947, Serial No. 143,064

Term of patent 3½ years

(Cl. D26—14)

To all whom it may concern:

Be it known that I, Eberley R. Ethington, a citizen of the United States, and a resident of Santa Monica, California, have invented a new, original, and ornamental Design for a Combined Mounting and Protective Housing for Loud Speakers, of which the following is a specification, reference being had to the accompanying drawing, forming part thereof.

Referring to the drawing:

Figure 1 is a perspective view of a combined mounting and protective housing for loud speakers, showing my new design;

Figure 2 is a top plan view thereof;

Figure 3 is a side elevation of the device as viewed from the right side of Figure 2;

Figure 4 is a side elevation thereof as viewed from the under side of Figure 2; and

Figure 5 is a bottom plan view of the device as seen from the under side of Figure 4.

I claim:

The ornamental design for a combined mounting and protective housing for loud speakers, as shown.

EBERLEY R. ETHINGTON.
